THERMOMETER HOLDER

Adam J. Grodin, Forest Hills, N.Y., assignor to Eisele & Company, Inc., Clifton, N.J., a corporation of Tennessee

Filed June 13, 1968, Ser. No. 12,330

Term of patent 14 years

U.S. Cl. D52—7
Int. Cl. D3—99

FIG. 1 is a front elevational view of a thermometer holder showing my new design;

FIG. 2 is a side elevational view thereof, as viewed in the direction of arrow 2, in FIG. 1;

FIG. 3 is a side elevational view thereof, as viewed in the direction of arrow 3, in FIG. 1;

FIG. 4 is a rear elevational view thereof, as viewed in the direction of arrow 4, in FIG. 2;

FIG. 5 is a top plan view thereof; and

FIG. 6 is a bottom plan view thereof.

I claim:

The ornamental design for a thermometer holder, substantially as shown.
